ACOUSTICAL CEILING UNIT

Fred W. Segerstrom, Perrysburg, Ohio, assignor to Johns-Manville Corporation, New York, N. Y., a corporation of New York

Filed Aug. 8, 1962, Ser. No. 71,215

Term of patent 14 years

(Cl. D18—2)

FIG. 1 is a top plan view of an acoustical unit showing the new design of the present invention;

FIG. 2 is a sectional view taken on line 2—2 of FIG. 1; and

FIG. 3 is an isometric view of the unit in an inverted position from that shown in FIG. 1.

I claim:

The ornamental design for an acoustical ceiling unit, as shown.
